COMBINED BOOK STAND AND MEMO PAD HOLDER

Kimio G. Obata, Webster Groves, Mo., assignor to Obata
Import and Export, Inc., a corporation of Missouri

Filed Mar. 9, 1962, Ser. No. 69,175

Term of patent 14 years

(Cl. D74—1)

FIG.6

FIG. 1 is a top plan view of a combined book stand and memo pad holder showing my new design,

FIG. 2 is a front elevational view thereof,

FIG. 3 is a side elevational view,

FIG. 4 is an elevational view of the side opposite thereto,

FIG. 5 is a rear elevational view, and

FIG. 6 is a top perspective view thereof.

I claim:

The ornamental design for a combined book stand and memo pad holder, substantially as shown.
